James O'Connor
Letters Patent

Oct. 14, 1835

The Schedule referred to in these Letters Patent, and making part of the same, containing a description in the words of the said James O'Connor himself of his Improvement in Canal Boats for the Transportation of Merchandise.

Schedule or Specification of James O'Connor's improved Canal Boat for carrying merchandise and general freight to be used when transhipment from Canal to Rail or other roads and vice versa is necessary.

Construct the hull of the Boat, Flat or Show in all respects similar to those used on the Canal to be navigated. Construct a short Stern deck such as is used day four or five feet long next to which deck or dock is a 6 foot long cabin. Also construct a short bow deck say four or five feet long.

These decks and cabin will occupy from fourteen to sixteen feet in length of the Boat's show, or Flat. The remaining, or greater part of the Boat to be covered

filling them again, thus the honey is secured in summer time, by the bowls and drawers, in abundance; way making you or the other bowls a drawal can be removed with the slightest danger or trouble. As soon as the bees have run their combs to the holes behind the door, two other large bowls are screwed on, hole upon hole, behind the door, with some of the above mentioned cement, thickly smeared around the holes; when the bees are removed, a great quantity of bees will come out of the full into the empty bowls, ~~and~~ after they have worked their way into the empty ones they are removed ~~and~~ others replaced for the reception of more, &c. From the main body below, the honey is taken in winter time, when a door is opened in a cold morning before the palace is quite full, the bees will retire and become stiffened, then the combs are cut through right in the middle, between the sticks, with a sharp pointed, thin boned, tin plate, and a stick with its ash-
win removed. Thus a stick full can be taken out from the copper banquet halls every morning, until the one half and is carried away. In the spring these sticks are all to be replaced; thus the honey of every other half can be taken out every winter. By pursuing this plan the bees continue in making new combs, and filling up every other half and every summer, &c. These are some of these "fortifications" so large as to contain upwards of three large heads ~~and~~ commended with eighteen hives. One hundred and fifty gallons of honey have been taken out of one house in one year. The superiority of this invention over anything of the kind hitherto in use, is unquestionable. ~~and~~ individuals who have made ~~use~~ of this plan all concur in saying that the bees thrive better, ~~and~~ make ten times the quantity of honey which they did on the former plan.

Know all men by these Presents. That we the undersigned have had a perfect trial ~~and~~ examination of Mr. Gove's Patent Bee House, two summers ~~and~~ we ~~consciously~~ believe, that it will answer every purpose as it is recommended; any person wishing to see a honey comb built in two summers, eight feet long ~~and~~ four wide can be gratified with the sight by calling with us. Jacob Jackson, Cornelius Rockburn, Mrs. Trout, Philip Gable, Perry Banks County Pa. December 1, 1834.

On this 36th day of May, 1835, before the subscriber a Justice of the Peace ~~and~~

and for said County, personally appeared the aforesaid William Grays,
and made solemn oath according to law, that he verily believes himself
to be the true and original inventor and discoverer of the invention above
specified and described for a Bee House, and that he is a citizen of the
United States.

W. H. Wharton.

Given under my hand at the City of Washington this 12th day of June A.D.
1835. Andrew Jackson

By the President John Forsyth, Secretary of State,
"I do certify that the foregoing Letters Patent, were delivered to me on the
18th day of June A.D. 1835, to be examined and I have examined the same
and find them conformable to law.

B. P. Butler Attorney General of the
United States
